The ornamental design for a control unit for a surveillance system, as shown and described.

DESCRIPTION

FIG. 1 is an isometric view from the left and front of a control unit for a surveillance system showing my new design;

FIG. 2 is a top plan view thereof;

FIG. 3 is a right side elevational view thereof; the left side elevational view being the same;

FIG. 4 is a rear elevational view thereof; and,

FIG. 5 is a bottom plan view thereof.

FIG. 2

FIG. 4

FIG. 3

FIG. 5
